UNITED STATES PATENT OFFICE.

ALFRED L. WEISSENTHANNER, OF NEW YORK, N. Y., ASSIGNOR TO THE PHOENIX CAP COMPANY, A CORPORATION OF NEW YORK.

METALLIC CLOSURE FOR BOTTLES, JARS, &c.

SPECIFICATION forming part of Letters Patent No. 745,702, dated December 1, 1903.

Application filed April 8, 1903. Serial No. 161,575. (No model.)

To all whom it may concern:

Be it known that I, ALFRED L. WEISSENTHANNER, a citizen of the Republic of France, and a resident of the city, county, and State 5 of New York, have invented certain new and useful Improvements in Metallic Closures for Bottles, Jars, &c., of which the following is a specification.

My invention relates to metallic closures for bottles, jars, &c., and more particularly to sheet-metal stoppers having a crown portion and a securing-flange inclosing a suitable sealing medium adapted to be bent into locking-contact with the shoulder formed 15 near the mouth of the bottle or jar.

As heretofore constructed the crown portion of stoppers of the character referred to have a depending flange portion which incloses a sealing medium and projects down 20 more or less from the mouth of the bottle. The flange portion is made of a separate ring of metal, the same being slightly flanged at the top to overlie the crown and having a detachable connection to enable it to be readily 25 released from the bottle to remove the stopper. Stoppers of this construction have been found to be defective for the reason that although the sheet metal from which they are constructed is ordinarily provided with a protective coating the edges of the metal, and particularly the lower edge of the flange portion of the crown, are not protected and often become oxidized or corroded to such an extent as to discolor and destroy the sealing 30 medium, and thus injure the contents of the bottle or vessel. Stoppers of this construction are also defective for the reason that the parts thereof are not secured together. When the stopper is released from the mouth 35 40 of the vessel, the parts of the stopper fall apart, and if the contents of the vessel are confined under pressure the parts of the stopper are apt to fly in various directions.

My invention has for an object to provide 45 a construction whereby these difficulties are overcome.

More particularly the main object of my invention is to so construct the crown portion of the stopper that the unprotected edge 50 thereof will not come in contact with the sealing medium or with the mouth of the bot-

tle or vessel; also to provide a construction whereby the parts of the stopper will not be separated and scattered in various directions when the stopper is removed from a vessel 55 the contents of which are confined under pressure.

These and other objects of my invention will more fully appear from the following description.

My invention consists in the novel parts, improvements, and combinations herein shown and described.

The accompanying drawings, which are referred to herein and made a part hereof, 65 illustrate two embodiments of my invention and serve, in connection with the description herein, to explain the principles thereof.

Of the drawings, Figure 1 is a side elevation of a stopper constructed in accordance 70 with my invention, the same being shown as applied to the mouth of a bottle. Fig. 2 is a plan view of the stopper removed from the bottle. Fig. 3 is a vertical central section of the same. Fig. 5 is a sectional view, on an 75 enlarged scale, illustrating a certain detail. Fig. 4 is a perspective view of the crown portion of the stopper. Fig. 6 is a vertical central section illustrating a modification, and Fig. 7 is a perspective view of the crown portion of the stopper shown in Fig. 6.

In accordance with the embodiment of my invention illustrated in Figs. 1 to 5, inclusive, the stopper consists of a crown portion 1, a flange portion 2, and a suitable sealing 85 medium 3. The crown 1 consists of a disk of metal, the same being suitably stiffened by having its outer edge folded over onto the top of the disk to form a bead or rim 4, as clearly shown in Fig. 4. The flange portion 2 consists of a band of sheet metal having its ends 90 detachably secured by any suitable means, as by a tongue 5, struck up from the metal of the band near one end and adapted to pass through an opening 6 near the other end of 95 the band. By pressing outwardly the exposed end 7 of the band the tongue 5 may be disengaged from the opening 6, so as to release the band from the bottle or vessel.

Where the contents of the vessel are confined under pressure, the stopper as a whole 100 will be projected from the mouth of the bot-

tle or vessel with considerable force, and if the parts of the stopper, and particularly the metallic parts, are not so constructed that they will not become detached as they are projected from the mouth of the bottle they are apt to cause injury to surrounding objects or to the person opening the bottle. A thin metallic disk as the crown portion 1 would be especially dangerous if it should become separated from the band portion and be projected at a high velocity. To overcome this objection to the construction as thus far described, the crown portion 1 of the stopper is secured to the flange portion. This may be accomplished in any suitable way. As shown, the crown portion 1 is provided with a suitable tongue or projection 8, which is adapted to pass outwardly through an opening 9 in the flange portion 2, which opening in the particular embodiment of the invention shown is adjacent to the upper edge of the flange portion, said opening being preferably located on the line where the upper portion of the ring 2 is bent over to overlie the crown portion 1. The free end of the tongue 8 is bent over onto the top of the flange 2, which overlies the rim of the crown portion 1, as clearly shown in full lines in Fig. 5, said part of the crown portion being slightly bent down into the recess formed between adjacent ends of the rim 4.

In accordance with the construction in Fig. 6 the crown portion 10 is not provided with a rim such as the rim 4 of the construction above described. Where the crown portion is not provided with an upwardly-turned rim, it is preferably formed of a non-corrosive metal, such as nickel or an alloy. The crown 10 is provided with a tongue 11, adapted to project through an opening 12 in the flange portion 2 of the stopper in a manner similar to that described in connection with the previous form of the device. Where the crown portion of the stopper is made of non-corrosive metal or where corrosion of the metal is not likely to occur or if it occurs is not objectionable, the crown portion of the stopper may be provided with an integral depending flange, and the connections between the crown and the securing-flange may be made at some other point than at the point shown.

It will be seen that in each form of the device described there is no unprotected edge of corrosive metal so located as to come in contact with the mouth of the bottle or with

the sealing medium adjacent to the mouth of the bottle. In the form of the device first described, moreover, there is no unprotected edge of metal which can come in contact with any portion of the sealing medium. The parts of the stopper, whether made of corrosive or non-corrosive metal, moreover, are so secured together that they will not be scattered when the stopper is projected from the mouth of a bottle at a high velocity. 65

My invention in its broader aspects is not limited to the particular construction shown and described nor to the precise construction by which it may be carried into effect, as many changes may be made in the construction without departing from the main principles of the invention and without sacrificing its chief advantages. 70

Having thus described my invention, what I claim, and desire to secure by Letters Patent, is— 75

1. A sheet - metal stopper comprising a crown portion and a separate flange portion, said parts being so secured as not to be separated when projected from the mouth of a vessel. 80

2. A sheet - metal stopper comprising a crown portion having an upwardly - turned rim and a separate flange portion having an inwardly-turned edge adapted to overlie said rim, substantially as described. 85

3. A sheet - metal stopper comprising a crown portion having an upwardly - turned rim and a separate flange portion having an inwardly-turned edge adapted to overlie said rim, said crown and flange portions being so secured together as not to become separated when projected from the mouth of a vessel, substantially as described. 90

4. A sheet - metal stopper comprising a crown portion having an upwardly - turned rim and a separate flange portion having an inwardly-turned edge adapted to overlie said rim, and means for securing said parts together, said means consisting of a finger on one part adapted to engage an opening in the other, substantially as described. 95

In testimony whereof I have signed my name to this specification in the presence of two subscribing witnesses.

ALFRED L. WEISSENTHANNER.
